UNITED STATES PATENT OFFICE

111,329

DESIGN FOR A COMBINATION HANDBAG AND WHISTLE

Louis Schumacher, Brooklyn, N. Y.

Application June 18, 1938, Serial No. 77,926

Term of patent 3½ years

To all whom it may concern:

Be it known that I, Louis Schumacher, a citizen of the United States and resident of New York city, Borough of Brooklyn, in the county of Kings and State of New York, have invented a new, original, and ornamental Design for a Combination Handbag and Whistle, of which the following is a specification, reference being had to the accompanying drawing, forming a part thereof, and of which Figure 1 is a view in front elevation of a combination handbag and whistle showing my new design, and Figs. 2 and 3 are views thereof in elevation of the opposite ends thereof.

The characteristic feature of the design resides in the combination of a handbag with a whistle forming a part of the handle of the handbag.

I claim:

The ornamental design for a combination handbag and whistle, substantially as shown and described.

LOUIS SCHUMACHER.
